United States Patent Office.

FREDERICK S. BIDWELL, OF MYSTIC BRIDGE, CONNECTICUT.

Letters Patent No. 97,860, dated December 14, 1869.

COMBINED SHOVEL AND SIFTER.

The Schedule referred to in these Letters Patent and making part of the same.

To all whom it may concern:

Be it known that I, FREDERICK S. BIDWELL, of Mystic Bridge, in the county of New London, and State of Connecticut, have invented certain new and useful improvements in the domestic implements known as Fire-Shovels; and I do hereby declare that the following is a full and exact description thereof.

The object of my invention is to more readily and conveniently sift or separate from the coals and cinders the ashes and fine dirt, and dispose of both the parts with little labor or expensive apparatus, by means of a shovel, which may also be used in the ordinary manner, and without making any holes in the shovel proper, or otherwise involving a liability to drop ashes or the like.

My invention provides very convenient means for emptying the ashes and cleaning the device, and repairing or renewing either part.

I will first proceed to describe what I consider the best means of carrying out my invention, and will afterwards designate the points which I believe to be new therein.

The accompanying drawings form a part of this specification.

Figure 1 is a plan view of the shovel;

Figure 2 is a side view, with the parts in their ordinary positions; and

Figure 3 is a central longitudinal section, with the parts in the position which they are made to assume to allow of emptying the ashes.

Similar letters of reference indicate like parts in all the figures.

A is the handle, and B, the body of the shovel. It may be made of stout sheet-metal, or other suitable material, and is, by preference, in the ordinary form, but somewhat deeper than usual.

A light grate, C, is mounted in the shovel, in the position represented, and the mixture of ashes and cinders is taken in the shovel with this grate down in the position shown in fig. 2. The material is shaken with the shovel in this condition, and, after the ashes have sifted through the grate C, into the bottom of the shovel, the cinders may be removed or dumped from the top of the grate C, and then, by holding the shovel over the ash-box or other vessel, with the front edge downward, and lifting the grate C, the ashes are dumped into such second vessel, and the shovel is again ready for use.

The form and arrangement of the several parts are represented very clearly, and will be understood from a very brief description.

The principal material of the grate may be stout sheet-iron, steel, semi-steel, or analogous light and

strong material, and it may be cut in dies by any approved machinery.

The back edge of the grate is strengthened by a stout cross-piece, m, having trunnions, m^1 m^2 , thereon, which are supported in holes in the sides of the shovel.

A small plain cylindrical hole on one side of the shovel is indicated by b¹.

An oblique slot in the other side of the shovel is indicated by b².

The lower edge of the slot b² is bent backward, or extended horizontally, as represented by b³.

The shovel is made complete, and provided with a swivelling-piece, D, turning on a centre, d, fixed therein.

The grate is also made separately, as represented, the sheet-metal part C being firmly riveted or otherwise secured to the stouter cross-piece m, and also riveted or otherwise secured to the thumb-piece E, by which the grate may be conveniently lifted with the same hand that holds the shovel.

To fit the grate properly into the shovel, one trunnion, m^1 , of the grate C is inserted in the hole b¹. Then the other trunnion, m^2 , is pushed down into the slot b² until it reaches the base of that slot, and is then drawn backward into the notch or rest b³. It is now retained there by turning down the button or swivelling-piece D.

This latter should turn rather stiffly on the rivet d, so that it will remain in the position in which it is left.

I do not confine myself to the entire form and construction of the grate here represented. Its curvature may be varied within wide limits, or it may be made perfectly plain, or even curved downward, without totally preventing the performance of its useful functions.

So also the strengthening-piece m and the thumb-piece may be attached by other means, or may, by proper processes, be made in one piece with the main body of the grate.

The shovel-body may be varied in dimensions and in material, as will be obvious.

The trunnions may be formed in one piece with the body of the grate, instead of an added piece, and the grate may be made with round or other-shaped holes, of suitable size, instead of with the long rectangular apertures represented, and which are, for obvious reasons, generally considered preferable.

I claim—

1. The combination of a fire-shovel with a grate or strainer, fitted therein, when the latter is adapted to be lifted, to allow the removal of the ashes, substantially as herein described.

2. A fire-shovel, having a grate or sieve contained within it, and means, D d , or their equivalent, for disconnecting the same at will, substantially as and for the purposes herein specified.

3. The within-described general combination, construction, and arrangement of a shovel-body, B, with hole b^1 and slot $b^2 b^3$, the grate or sieve C, with trunnions $m^1 m^2$, and the fastening-button D, turning on

centre d , all as herein specified, and for the purposes herein set forth.

In testimony whereof, I have hereunto set my name, in presence of two subscribing witnesses.

FREDERICK S. BIDWELL.
